UNITED STATES PATENT OFFICE.

MIKE MARKOVICH, OF BOSEVAC, JUGO-SLAVIA, ASSIGNOR OF ONE-HALF TO DAVID STUPICH, OF SOUTH WELLINGTON, BRITISH COLUMBIA, CANADA.

SNOW-GATHERING DEVICE.

1,397,436.

Specification of Letters Patent.

Patented Nov. 15, 1921.

Application filed October 22, 1920. Serial No. 418,865.

To all whom it may concern:

Be it known that I, MIKE MARKOVICH, a citizen of Jugo-Slavia, residing at Bosevac, in the District of Ivok and Kingdom 5 of Jugo-Slavia, have invented certain new and useful Improvements in Snow-Gathering Devices, of which the following is a specification.

The primary object of the invention is 10 the provision of a gathering means for snow and ice for clearing a trackway during the continuous travel so that the oncoming train may freely pass over the cleared track.

15 A further object of the invention is to provide a car adapted for breaking up and collecting snow and ice for transferring the same to a rearward position laterally of the path of travel so that the track is readily 20 cleared for the passage of trains thereover following the operation of the device.

With these general objects in view, the 25 invention consists of the novel combination and arrangement of parts hereinafter more fully described, illustrated in the accompanying drawings and pointed out in the appended claims.

In the drawings, wherein like reference 30 characters designate corresponding parts throughout the several views,

Figure 1 is an elevational view of the device mounted for use upon a track,

Fig. 2 is a top plan view thereof with parts removed,

35 Fig. 3 is an enlarged longitudinal sectional view of the forward portion of the device,

Fig. 4 is a top plan view of a forward portion of the same,

40 Fig. 5 is a vertical transverse sectional view taken upon line V—V of Fig. 3,

Fig. 6 is an enlarged vertical longitudinal sectional view of a rear portion of the device,

45 Fig. 7 is a vertical transverse sectional view taken upon line VII—VII of Fig. 6, and

Fig. 8 is an enlarged detail view of the adjusting means for the gatherer.

50 Referring more in detail to the drawings, my invention broadly consists of an elongated conveyer casing 10 of tubular formation having a car 11 at its rear end, the casing and car being provided with similar wheels 12 whereby the device is mounted

for travel upon the rails 13 of a track such as an ordinary line of railroad track. An endless belt 13' passes over a drum 14 adjacent the forward open end 15 of the casing 10 and a drum 16 journaled in the car 60 11 at a point elevated above the said entrance end 15 of the casing. The casing 10 has an angular bend 17 intermediate its ends with an inclined rear portion 18 entering said car 11 while the lower ply of the 65 belt 13' passes over a transverse roller 19 adjacent the bend 17 of the casing.

An inclined plate or nose 20 upon the bottom 21 of the casing 10 at the forward end thereof has a serrated edge 22 for projecting into the bank of snow upon the track 13 whereby the snow is forced into the open end 15 of the casing during the forward movement of the device. The belt 13' is provided with transverse cleats 23 for carrying the snow along the false bottom 24 of the casing 10 and upwardly into the car 11 during the travel of the belt 13' in the direction of the arrow indicated in Fig. 3 of the drawings. Oppositely projecting 70 chutes 25 are carried by the car 11 for receiving the snow from the upper end of the false bottom 24 when carried onto the platform 26 by the conveyer belt 13'. An electric motor 27 in a side housing 28 of 75 the car 11 is operatively connected to the rear upper drum 16 for turning the same and furnishing motor power for the belt 13' while a plurality of motors 29 operatively connected to any of the wheels 12 desired 80 to furnish power for causing the device to travel along the rails 13.

An elevated track 30 upon the top 31 of the horizontal portion of the casing 10 has a car 32 mounted thereon for travel toward 95 and away from the forward end of the casing 10, the said track 30 projecting forwardly of said open end 15 to a point substantially above the cutting end 22 of the gathering plate 20. Upper and lower 100 shovels 33 and 34 respectively are pivoted in opposite posts 35 of the car 32 by means of parallel shafts 36 and 37 respectively while a lever 38 is operatively connected to the shovel 33 for shifting the same and 105 a smaller lever 39 controls the lower shovel 34.

The shaft 36 is provided with a gear 40 having a pair of pivoted pawls 41 for maintaining the same in adjusted position when 110

the shovel 33 is positioned as desired for use by means of the lever 38. Similarly, a gear 42 upon the shaft 37 is provided with retaining pawls 43 whereby the lower shovel 34 is maintained in its adjusted position relatively of the shovel 33.

Curved hinged sections 44 at the forward ends of the track rails 30 are adapted to engage over the forward wheels 45 of the car 10 for retaining the car at the forward extremity of its travel upon the track 30 whereby the shovels 33 and 34 are normally positioned in advance of and above the level of the gathering plate 20 for breaking down 15 the snow and ice during the forward travel of the device. A ladder 46 is provided for gaining access to the motor housing 28, it being understood that line wires 47 for the motor 27 and similar wires 48 for the motors 20 29 lead to any suitable source of electrical supply for furnishing current to operate the device.

The complete operation of the invention will be fully understood from this detailed 25 description thereof, the shovels 33 and 34 breaking down the snow to be gathered by the plate 20 during forward travel when positioned as best illustrated in Fig. 1 of the drawings. The conveyer belt 13' carries 30 snow into car 11 and from which it passes laterally over the inclined members 25 to the opposite sides of the track 13. The car 32 is provided with suitable steps 49 while depending arms 50 within the casing 10 free 35 the belt 13' from any ice that might accumulate thereon. The device possesses great strength and is capable of clearing a railroad track easily and quickly for permitting the free passage of trains thereover.

40 What is claimed as new is:—

1. A device of the class described comprising an elongated casing having an open forward end and adapted for travel upon a track, an endless conveyer within the casing, 45 a snow gathering plate at the forward end of the casing adjacent one end of the conveyer and breaking down means for snow mounted for travel upon the top of the casing normally positioned for use projecting forwardly and above said plate.

2. A device of the class described comprising an elongated conveyer member adapted for travel upon a track, rails upon the top of said conveyer member, a car mounted 50 for travel upon said rails, shovels adjustably

pivoted to said car, and adjusting and retaining means for said shovels.

3. In combination with a snow gatherer adapted for traveling upon a track, a car longitudinally movable thereon, shovels pivoted one above the other upon said car projecting forwardly of the car, and adjusting members carried by the car operatively connected to said shovels whereby the latter are adapted for relative adjustment. 60 65

4. A device of the class described comprising an elongated casing having a forward open end, a car at the rear end of the casing, motor driven wheels beneath the casing and car adapted for traveling upon a track, a snow gathering plate upon the bottom of the casing projecting at an incline forwardly thereof with a serrated edge, an inclined false bottom within the casing connected to said plate and extending rearwardly into 70 the car, oppositely projecting chutes carried by the car at the rear upper end of said false bottom, and a snow conveyer having one end adjacent the plate and its other end within the car above the level of said chutes 75 adapted for operation during the forward travel of the device.

5. A device of the class described comprising an elongated casing having a forward open end, a car at the rear end of the casing, 80 motor driven wheels beneath the casing and car adapted for traveling upon a track, a snow gathering plate upon the bottom of the casing projecting at an incline forwardly thereof with a serrated edge, an inclined 85 false bottom within the casing connected to said plate and extending rearwardly into the car, oppositely projecting chutes carried by the car at the rear upper end of said false bottom, a snow conveyer having one 90 end adjacent the plate and its other end within the car above the level of said chutes adapted for operation during the forward travel of the device, a track upon the top of the casing, a car mounted for travel thereon 100 adapted for normal positioning substantially above said plate when the device is in use, forwardly projecting shovels one above the other pivoted to said last named car, adjusting levers for said shovels, and retaining means for the shovels when in their 105 adjusted positions.

In testimony whereof I affix my signature.

MIKE MARKOVICH.
